UNITED STATES PATENT OFFICE.

LOUIS STEINBERGER, OF BROOKLYN, NEW YORK.

DIAPHRAGM FOR SOUND RECEIVERS AND MEANS FOR MOUNTING THE SAME.

Application filed January 24, 1921. Serial No. 439,410.

To all whom it may concern:

Be it known that I, LOUIS STEINBERGER, a citizen of the United States, and a resident of the borough of Brooklyn, city and State of New York, have invented certain new and useful Improvements in a Diaphragm for Sound Receivers and Means for Mounting the Same, of which the following is a specification.

10 My invention relates to an improved diaphragm mounting for sound receivers in general, the object of the invention being to so mount and construct a diaphragm upon sound receivers in order to effect a closed sound chamber below the diaphragm in order to increase the volume and sonority of the sound.

Other objects will appear from the subjoined specification and claim.

20 Referring to the drawings:

Fig. 1 is a view partly in section of a sound receiver adapted for use with telephones of a diaphragm constructed and mounted in accordance with my invention.

25 Fig. 2 is a section of the diaphragm and metal cup to which the diaphragm is secured by a ring coupling, the parts being shown separately.

In the drawing, 5 designates the exterior casing of a telephone receiver, same being made either of electrose, hard rubber or other suitable non-metallic insulating material, and having an open end across which the vibratory soft iron diaphragm 6 extends.

30 A hollow cup-shaped shell 12 of metal having in general the shape of a kettle drum is located within and conforms to the shape of the interior portion of the casing so as to be securely seated therein. The open end of this shell is closed by the diaphragm 6 which extends across the upper portion of the cup-shaped shell 12 and is hermetically secured by soldering, welding or other suitable means to the extending flange 13 of said cup-shaped shell whereby an internal chamber 14 is provided between the underside of the diaphragm 6 and the shell. The dia-

40 phragm 6 may in the alternative be securely and rigidly clamped to the flange 13 of the shell 12 by means of a coupling consisting of a ring-shaped member 20 which has a lower flange 21 extending inwardly and engages the underside of the flange 13. When

the diaphragm is thus in place the upper portion of the coupling is then bent around 55 to closely engage the diaphragm as at 22 and thus press the diaphragm downwardly and thereby hold the same tightly against the flange 13 of the metal cup shaped member 12.

60 By means of the structure as above described a sound chamber underneath the diaphragm is formed which is absolutely air tight and thus tends to increase the volume and sonority of the sound.

65 With the parts as above described in place the cap 7 is secured to the casing 5 in the usual way by screwthreaded attachment as at 8, thus securing the parts in position as shown for use.

70 The magnet elements are not particularly described. It is deemed sufficient only to say that they may be of any suitable form as my invention is in no way concerned with the details of the magnet whereby the diaphragm is caused to vibrate. Care must be taken however to hermetically seal the joint at 60 where the magnetic element 61 passes through the bottom 62 of the shell 12.

75 As changes of construction could be made 80 within the scope of my invention, it is intended that all matter contained in the above description or shown in the accompanying drawings shall be interpreted as illustrative and not in a limiting sense.

85 Having thus described my invention what I claim as new and desire to secure by Letters Patent is:

A sound receiver having an inner cup like shell with an outer annular flange 90 formed thereon, a diaphragm closing one end of said shell seated on said flange, and an annular coupling ring having in-turned flanges, the said coupling ring fitting over the edges of the diaphragm and of the annular flange of the shell, the flanges of the coupling ring directly and closely engaging respectively the diaphragm and the flange of the shell to form an air tight joint between the diaphragm and the shell thus forming a 100 unitary structure.

In witness whereof, I have hereunto set my hand at the borough of Manhattan, city and State of New York, this 14 day of January, 1921.

LOUIS STEINBERGER.
